CLAIM

The ornamental design for a filament-style LED array light, as shown and described.

DESCRIPTION

FIG. 1 is a front elevation view of a filament-style LED array light with the rear, left side, and right side views being identical, according to a first embodiment of the invention.

FIG. 2 is a top plan view thereof.

FIG. 3 is a bottom plan view thereof.

FIG. 4 is a perspective view thereof.

FIG. 5 is a front elevation view of a filament-style LED array light with the rear, left side, and right side views being identical, according to a second embodiment of the invention.

FIG. 6 is a top plan view thereof.

FIG. 7 is a bottom plan view thereof; and,

FIG. 8 is a perspective view thereof.

The features shown in broken lines do not form part of the claimed design.
